US0D1040973S

(12) **United States Design Patent** (10) **Patent No.:** **US D1,040,973 S**
(45) **Date of Patent:** **** Sep. 3, 2024**

(54) **FAUCET**

(71) Applicant: **Wenzhou Furuisi Building Materials Co., Ltd**, Wenzhou (CN)

(72) Inventor: **Chunhe Qiu**, Wenzhou (CN)

(73) Assignee: **WENZHOU FURUISI BUILDING MATERIALS CO., LTD**, Wenzhou (CN)

(**) Term: **15 Years**

(21) Appl. No.: **29/934,172**

(22) Filed: **Mar. 25, 2024**

Related U.S. Application Data

(60) Continuation-in-part of application No. 29/914,544, filed on Oct. 18, 2023, now Pat. No. Des. 1,029,201, which is a division of application No. 29/878,600, filed on Jun. 25, 2023, now Pat. No. Des. 1,012,246, and a continuation-in-part of application No. 29/831,603, filed on Mar. 22, 2022, now Pat. No. Des. 1,009,224, said application No. 29/878,600 is a continuation-in-part of application No. 29/831,603, filed on Mar. 22, 2022, now Pat. No. Des. 1,009,224.

Primary Examiner — Robert A Delehanty

(74) *Attorney, Agent, or Firm* — Andrew C. Cheng

(57) **CLAIM**

The ornamental design for a faucet, as shown and described.

DESCRIPTION

FIG. 1 is a front perspective view of a faucet in accordance with my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the faucet that form no part of the claimed design.

1 Claim, 8 Drawing Sheets
